LOUIS SCHWARTZBERG, OF CHICAGO, ILLINOIS.

EGG-CASE.

1,335,300.

Specification of Letters Patent. Patented Mar. 30, 1920.

Application filed March 26, 1919. Serial No. 285,147.

To all whom it may concern:

Be it known that I, LOUIS SCHWARTZBERG, a citizen of the United States, and a resident of the city of Chicago, in the county of Cook 5 and State of Illinois, have invented certain new and useful Improvements in Egg-Cases, of which the following is a specification.

My invention relates to improvements in 10 egg cases or containers and has special reference to the provision of a strengthening or stabilizing means in such containers whereby the shifting of the eggs in each row of cells is avoided and a considerable 15 portion of the breakage is eliminated.

Among the other objects of my invention is the provision of means for cushioning the 20 ends of the cells so that the longitudinal shifting of the eggs will prevent the breakage of the latter; means for interlocking the respective rows of cells with said cushioning means; and means for coöordinating the cells with the flats.

Divers other objects will be obvious to 25 others skilled in this art after an understanding of my invention is had, and I prefer to accomplish the objects of my invention by the means and in the manner substantially as hereinafter described and as 30 more particularly pointed out in the claims, reference being now had to the accompanying drawings which form a part of this specification, in which,—

Figure 1 is a fragmentary perspective 35 view of a plurality of cells having portions of the flat broken away to clearly illustrate the relative location of the parts.

Fig. 2 is a perspective view of the securing means having the upper section of cells 40 broken away.

Fig. 3 is a top plan of a portion of the upper section of cells.

Fig. 4 is a section on line 4—4, Fig. 3, showing the disposition of a plurality of sections of cells, and means of interlocking with the cushioning means.

Fig. 5 is a section on line 5—5, of Fig. 4, and looking in the direction of the arrows.

Fig. 6 is a perspective view of a crate 50 made in accordance with my invention the walls being broken away to disclose another type of filler structure.

Fig. 7 is a vertical section taken through several cells of a filler removed from the 55 crate.

Fig. 8 is a perspective of a fragmentary portion of one of the cell walls.

As is the usual custom, the cell sections are placed in suitable compartments within a crate having end walls A and longitudinal 60 side walls B, said cells being stacked one upon the other, and having flats C interpositioned between the respective sections of cells to divide them and provide the usual individual compartments for the eggs. The 65 cushioning means I have mentioned comprises a strip of cellular or corrugated board 10, positioned vertically at the ends of each section of the crate and have suitable horizontally disposed recesses or channels 11 cut 70 into the same, at approximately the horizontal plane of each of the flats C. The cells comprise suitable longitudinal strips 12 and transverse strips 13, of cardboard, strawboard or the like, that are slotted substantially one-half of their transverse width so that they may be positioned at approximately right-angles to each other when in use, in the manner shown in the drawings, and interlocked in such position so that they 75 may be collapsed whenever desired to have them knocked down.

The walls 12 are preferably disposed longitudinally of the crate, while the walls 13 are positioned transversely thereof, and one 80 of the latter walls 13, preferably the next to the last wall, indicated by α , I prefer to make slightly wider or taller, so that an extension or flap 14 is provided that is of sufficient width to extend across the last row 85 of cells. The outer edges of these flaps or extensions are then bent back upon themselves, as at 15, to provide a suitable upstanding flange, as shown, that is adapted to snugly fit into the respective recess or 90 channel 11 in the cushioning structure 10. After the flap 14 has been inserted in the recess 11, the edges of the flat C are forced into the corner of the angle formed by the extension and the flange, and the same then 95 pushed down into position. As these extensions or flaps 14 are positioned adjacent each end of the cell sections, the flat C will securely lock the cells in position in their respective recesses 11, and in order that the 100 eggs may be observed, suitable fenestra 16 are provided in the flap in the manner shown. I do not, however, limit myself to the extension or flap located upon the next to last transverse wall of the cell sections,

for it is quite obvious any of the transverse walls may be thus constructed for the purpose of interlocking the same with the rigid portion of the crate, and I likewise wish it understood that the outer edges of the extensions may be interlocked or secured directly to the walls of the crate in the event it is found desirable to omit the cushioning structure 10. The longitudinal walls 11 have their ends extended beyond the end transverse walls 13, in the usual manner, and suitable vertical slots 17 are cut in the cellular cushioning board so that these end edges of the walls 12 may interfit therewith and be further prevented from moving laterally.

After the cells and flap have been assembled in the manner described and have been filled with eggs the top section of cells has its flaps 14 turned over on to the wall A of the crate and secured thereto by tacks 18 or otherwise, and the cover of the crate is then nailed into place. It may be found desirable to elongate or widen the flap 14, as shown in Fig. 2, and double the fabric by 25 folding it back upon itself along its outer edge, as shown at 19 in Figs. 2 and 4, which will provide a reinforcement that prevents the flap from pulling away from its securing means.

As above described, it will be obvious that the cells, having been locked into position at their ends, are prevented from any longitudinal movement within the crate, and the shocks and blows which usually strike the crates from the ends will not be transmitted directly to the eggs.

It will be obvious that divers modifications or refinements of this invention may be made without materially departing from the principles involved. For example, in Figs. 6, 7, and 8, I have illustrated a slightly modified construction wherein the cushioning pads 10-11 are omitted and the next to the last vertical walls α are provided with flaps 20, that are wider than the flaps 14, shown in the preceding figures so that they may be folded back upon themselves to the plane of the wall α , as seen at 21, Fig. 7, and the facing portions of these flaps are provided with round openings, 22 and 23, respectively, the lower, 22, being smaller in diameter than the upper, 23, and the edges of these openings are beveled toward the outer surfaces of the flaps to reduce the angularity of the openings to avoid sharp corners coming in contact with the eggs. After the flaps 20 and 21 have been folded down, the edges of flat C are forced into the corners of the angles formed at the folds 60 in the flaps and then pushed down into position to extend the flaps 20 in the same manner as in the preferred form. Adjacent the intersection of the walls α with the transverse walls 12, the former are slotted vertically at 24 to receive elongated spurs

25, that are formed by cutting oblique slots 26 in the walls 12, as seen in Fig. 7. This permits the walls α to be bent in a long curve 27, instead of a sharp bend, as well as providing slight elasticity or give to the flaps and the adjacent structure until the flat 2 has been properly positioned, and thereafter prevents the movement of the structure and its contents after packing and assembly. I desire it understood that the drawings are merely diagrammatic for the purpose of illustration, and any modifications or changes therein are contemplated as being included within the scope of my invention as expressed in the appended claims. 80

What I claim is:

1. In an egg crate a plurality of cell sections each formed of intersecting walls, the walls adjacent opposite ends of each section being extended and folded over the transverse walls and folded back upon themselves to form pockets, and flats interposed between said sections of cells and co-acting with the pockets in said extended walls. 90

2. In an egg crate having side and end walls, a cushioning structure disposed upon opposite end walls, cells having a portion of their walls extended and folded to form transverse pockets which interfit with said cushioning structure, and flats interposed between said cell sections and engaging said pockets thereby interlocking the same with said cushioning structure. 95

3. In an egg crate a cell section comprising a plurality of parallel longitudinal walls, and a plurality of parallel transverse walls interfitted therewith, certain of said transverse walls being wider than the remaining walls and adapted to be folded over a portion of the cell and extended to engage the adjacent walls of the crate and separate means for securing said extended portions to said crate. 100

4. An egg crate comprising a boxlike structure, cushioning means inside opposite walls of said structure and provided with horizontal recesses or channels, cell sections formed of intersecting walls, extensions on certain of said walls that are folded over a portion of the cells and have their edges fitted into said channels, and flats disposed upon the tops of each cell section and co-acting with the portions of said extensions fitted in said channels. 110

5. In an egg crate, a cell section comprising a plurality of intersecting walls certain of said walls being wider than the remaining walls and folded over the cells to form pockets adapted to receive the partitioning element between adjacent cell sections. 125

6. In an egg crate, a cell section comprising a plurality of intersecting walls certain of said walls being provided with fenestral 130

extensions that are folded over the cells to form transversely disposed inwardly opening pockets.

7. In an egg crate, a cell section comprising a plurality of intersecting walls certain of said walls provided with extensions folded flat upon the tops of adjacent walls the end edges of said extensions being folded back upon themselves to provide pockets, and a flat resting upon the tops of said cell section with its opposite edges engaging said pockets.

8. In an egg crate, a cell section comprising a plurality of intersecting walls certain of said walls provided with flaps folded flat upon the tops of adjacent walls the end edges of said extensions provided with lateral flanges said extensions having openings in registry with the adjacent cells, and a flat resting upon the tops of said cell section with its opposite edges engaging said flanges.

9. In an egg crate, cell sections comprising a plurality of intersecting walls, partitioning flats upon the top of each cell section, and extensions on certain of the vertical walls of each cell section having recesses into which the end edges of said partitioning flaps are inserted. 25

10. In an egg crate, cell sections comprising a plurality of intersecting walls, a partitioning flat between each adjacent pair of cell sections, and upward extensions upon certain of the vertical walls of said sections and adjacent the ends of said sections having elements engaged by said partitioning flats. 30 35

Signed at Chicago, county of Cook and State of Illinois, this 16th day of September 1918.

LOUIS SCHWARTZBERG.
